Primary Examiner — Leanne Was-Englehart(74) *Attorney, Agent, or Firm* — Buchalter, a Professional Corporation(57) **CLAIM**

The ornamental design for a swing gate plate, as shown and described.

DESCRIPTION

FIG. 1 is a perspective view of a swing gate plate of my claimed design.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof; and,

FIG. 7 is a bottom plan view thereof.

The broken lines depict portions of the swing gate plate that form no part of the claimed design.
